HIGH-TEMPERATURE FAN

Carl Nygren, Michigan City, Ind., assignor to
Michiana Products Corporation, Michigan
City, Ind., a corporation of Indiana

Application April 28, 1945, Serial No. 590,754

4 Claims. (Cl. 230—134)

1

Fans or blowers for handling gases at high temperatures such as are used for recirculation in heat treating furnaces are necessarily subjected to weakening temperatures and to varying extremes in expansion and contraction, particularly when driven by water cooled shafts. With temperatures on the order of 1200 to 1800 degrees Fahrenheit in the gas propelling outer parts of the fan and temperatures below 200 at the shaft, there is great tendency for the parts or the whole to get out of dynamic balance or otherwise develop destructive stresses.

The principal object of this invention is to provide a well balanced structure in which the parts are allowed freedom in expanding and contracting individually and dynamic balance is continually maintained.

Generally speaking, this is accomplished by mounting the several blades between circular, wheel-like side members with freedom to expand and contract individually, axially, and radially.

A preferred embodiment of the invention for a 24-inch fan is shown in the accompanying drawings, but these specific illustrations and the corresponding description are used for the purpose of disclosure only and are not intended to exclude divers variations in the claims.

Figs. 1 and 2 are diagrammatic views of a double inlet fan and its associated parts in one form of installation;

Fig. 3 is a half longitudinal section through the axis of a hollow shaft and fan taken on the line 3—3 of Fig. 2, showing a specifically different fan structure;

Fig. 4 is a side elevation of one of the blades;

Fig. 5 is an end view of the blades shown in Fig. 4 looking downwardly from the upper end;

Fig. 6 is an edge view of the blade shown in Fig. 5 looking from either the left or right;

Fig. 7 is a face view of one of the auxiliary hub members;

Fig. 8 is a longitudinal section through one of the auxiliary hub members;

Fig. 9 is a half section of the wheel shown in Fig. 3 taken at right angles to the axis and a half end elevation;

Fig. 10 is an inside elevation of one of the side members;

Fig. 11 is a longitudinal section along the axis of one of the side members;

Fig. 12 is a half elevation of a single inlet fan corresponding to Fig. 3;

Fig. 13 is an elevation of one of the blades used in that fan;

2

Fig. 14 is an edge elevation of Fig. 13 looking from the right in that figure;

Fig. 15 is an end view looking down on Fig. 13,

Fig. 16 is a face view of one of the auxiliary hub members; and

Fig. 17 is a longitudinal section through that hub member on the axis of rotation.

In Figs. 1 and 2, 10 indicates a conventional form of masonry installation for a fan or blower 11 within which is a metal casing 11 for a double inlet fan 12 mounted on a hollow shaft 13 journaled in bearings 14 and driven by a motor 15 through a V-belt drive 16. The inlet side of the water cooling unit is shown generally at 17, and the return side is shown generally at 18.

Water cooling is ordinarily used in fan constructions for propelling high temperature fluids such as the gases recirculated in heat treating furnaces.

20 The double inlet fan shown in Figs. 3—11 (Sheets 2 and 3) includes two wheel-like side pieces generally indicated by 19, twelve blades 20, and two auxiliary hub members generally indicated by 21.

Each side member includes a hub member 22, 25 a series of spokes or vanes 23, and a ring-like rim 24, which forms the shroud of the fan.

On the inside of each shroud 24 there are twelve radial grooves 25 to receive the edges of the blades 20 and hold them for driving the air 30 but with freedom to expand radially, axially, and circumferentially as occasion may require.

Each auxiliary hub member 21 includes a hub portion 26 and a flange 27 provided with twelve slots or notches 28 to receive and hold the inner 35 end portions of the blades 20 for driving but with freedom to expand in all directions as occasion may require, and also freedom to move radially and axially.

Each blade 20 is a generally rectangular flat 40 plate with its inner corners cut away at 29 to provide inlets for the fan. At each side the blade is thickened to form a sort of rib 30 which is machined on the opposite faces to enter the grooves 25 with a push fit in the ordinary construction. Adjacent to the inner end, each blade also has thickened portions 30 machined on opposite faces to be received within the notches 28 with a like push fit, but with the freedom described.

50 This arrangement of blades, side members, and auxiliary hub members provides an appropriate assembly for wheel construction and leaves only the requirement for restraining the blades from outward movement under centrifugal force individually or collectively. This may be taken care of

by any sort of shoulder arrangement by which the blades and side pieces are interlocked or the blades are made fast against the outward movement. In this illustration, that is accomplished by the simple expedient of providing each shroud 24 with an inwardly directed annular rib or flange 31 against which shoulders 32 at the outer corners of the blades come to rest under centrifugal force. This restraint is all that is needed and leaves the blades, side members, and auxiliary hub members free to move relative to each other in expanding and contracting, and allows for the differences in expansion due to the variations in temperature between the outer portions of the fan and those inner portions under the strong influence of the water cooled shaft.

Alternative expedients for restraining the outward movement of blades relative to shrouds will be readily designed by engineers to suit individual preference and the requirements of production. For example, in order to avoid having to machine the grooves 25 up to the ribs or flanges 31, the latter may be omitted, and each blade provided with a shoulder adjacent to the corners 29 for resting against the annular shoulders 34 and the side members 19, or both may be used.

The side members are here shown made in one piece and the auxiliary hub members in separate pieces, but this, of course, is a matter of choice and design.

The side members and the auxiliary hub members are driven from the water cooled shaft through three keys 35 equally distributed around the shaft and fitted at their parallel sides only to key slots having parallel sides. This provides freedom of expansion between the water cooled shaft and the heated hub members while maintaining a proper driving connection through the keys.

The left wheel member has its hub portion 22 resting against a shoulder 38 on a shaft 13, while the right wheel member has its hub portion 22 held assembled against the intermediate auxiliary hub portions by a collar 39 threaded on the shaft 13 and locked by a washer 40 having a tongue 41 in a slot 42 in the shaft and a wing 43 bent into a slot 44 in a lock nut 45. The collar 39 will be set up, wrench tight, and then backed off an amount determined by calculations or empirically to allow for the necessary expansion, which will depend upon the alloys used and the temperatures involved.

Figs. 12-17 (Sheet 4) show a similar fan construction for a single inlet fan in which the parts correspond throughout to those shown in Figs. 3-11, except that the left wheel member 119 is a disk to close the corresponding side of the fan and the blades 120 have the left side made to correspond, as will appear from Figs. 12 and 13. Otherwise, it is deemed sufficient to apply corresponding reference numerals to the parts in Figs. 12-17.

Side member 19 is provided with an annular rib 47 in the area adjacent to the shoulder 34 but on the other side of the shroud 24. This provides for a special strength to resist the high tensile stresses due to centrifugal forces and the natural tendency under those forces to stretch the shroud members. These ribs also make convenient grinding stock when the side members are being given the initial balance.

The side members, the blades, and the auxiliary hub members will in many cases have to be made of some kind of heat resisting alloy which will be determined largely by the tempera-

tures under which the fan is to be used modified by the corrosiveness of the atmosphere in which it is to be used. Some alloys providing very high strength and resistance to high temperatures do not offer sufficient resistance to corrosion for a long period of service, and some alloys especially adapted to resist certain types of corrosion are relatively weak as compared with many of those which have high strength and high resistance to temperatures. The choice of the alloy will determine the engineering design and to some extent the clearances and tolerances, but the following will serve as an example. The clearance between the blades and the shroud members and hub members may be plus .002" minus .003". When the grooves 25 are made with a milling cutter, they can be finished close up to the ribs 31 as shown. But the clearance between the ends of those grooves and the corresponding shoulders 32 on the blades may be considerable as compared with the other clearances, for centrifugal force will hold the blades in their proper relation in use. The fit between the hub members and the shaft may be plus .002" minus .000". This is on the assumption, as preferred, that the shaft is made of carbon steel and water cooled and the hub members are of a selected alloy.

According to the preferred procedure, the castings are machined and balanced. Afterwards, they are annealed at a temperature above that expected to be encountered in service. Then, with finishing touches here and there the fans are assembled and put through the final balancing.

I claim:

1. In a centrifugal fan, a plurality of blades in circular arrangement about a common axis of rotation with their inner portions converging inwardly toward said axis and their outer portions diverging outwardly from said axis, side pieces having hubs fixed against relative movement on a shaft and having shrouds grasping the outer portions of the blades and interlocked therewith for normal rotation capable of appreciable relative movement in expanding and contracting, flanges on the shrouds limiting the bodily outward movement of the blades, and a hub member interlocked with the inner portion of each blade with freedom for appreciable relative movement in expanding and contracting in a direction radial of the axis of rotation.

2. In a centrifugal fan, a plurality of blades in circular arrangement about a common axis of rotation with their inner portions converging inwardly toward said axis and their outer portions diverging outwardly from said axis, side pieces having hubs fixed against relative movement on a shaft and having shrouds grasping the outer portions of the blades and interlocked therewith for normal rotation capable of appreciable relative movement in expanding and contracting, flanges on the shrouds limiting the bodily outward movement of the blades, and a hub member having a slot receiving the inner end portion of each blade with freedom for appreciable relative movement in expanding and contracting in a direction radial of the axis of rotation.

3. In a centrifugal fan, a plurality of blades in circular arrangement about a common axis of rotation with their inner portions converging inwardly toward said axis and their outer portions diverging outwardly from said axis, side pieces having hubs fixed against relative move-

ment on a shaft and having shrouds grasping the outer portions of the blades and interlocked therewith for normal rotation capable of appreciable relative movement in expanding and contracting, engaging flanges and shoulders on the shrouds and blades limiting the bodily outward movement of the blades, and a hub member interlocked with the inner portion of each blade with freedom for appreciable relative movement in expanding and contracting in a direction radial of the axis of rotation.

4. In a centrifugal fan, a plurality of blades in circular arrangement about a common axis of rotation with their inner portions converging inwardly toward said axis and their outer portions diverging outwardly from said axis, side pieces having hubs fixed against relative movement on a shaft and having shrouds grasping the outer portions of the blades and interlocked therewith for normal rotation capable of ap-

preciable relative movement in expanding and contracting, portions of the shrouds overlapping portions of the blades to limit bodily outward movement of the blades, and a hub member concentric with the axis of rotation mounted between the side pieces and having a radial flange provided with an outwardly open radial slot receiving the inner end portion of each blade for normal rotation with freedom for appreciable relative movement in expanding and contracting in a radial direction.
